United States Patent Office

Des. 194,585
Patented Feb. 19, 1963

194,585

MULLION COVER

James C. Waring, Richmond, Va., and Leslie A. Fream,
Jefferson County, Ky., assignors to Reynolds Metals
Company, Richmond, Va., a corporation of Delaware

Filed Dec. 28, 1961, Ser. No. 68,109

Term of patent 14 years

(Cl. D13—6)

The FIGURE is a front perspective view of a mullion cover showing our new design.

The center thereof is broken away to indicate indefinite length.

We claim:

The ornamental design for a mullion cover, substantially as shown and described.
